AIR FILTER FRAME

Don J. Gonzalez, Louisville, Ky., assignor to
 American Air Filter Company, Inc., Louisville,
 Ky., a corporation of Delaware

Application September 8, 1952, Serial No. 308,453

2 Claims. (Cl. 183—44)

1

The present invention relates to a frame of novel construction for holding a filter element.

It is an object of the present invention to provide a metal frame which is so constructed that it may be painted or otherwise finished before final assembly.

Another object is to provide a filter frame which may be inexpensively and quickly made and which may be formed by bending and stamping operations.

A further object is the provision of a filter frame made up of portions rigidly fastened together by a simple, inexpensive structure.

These and other objects will be apparent upon consideration of the following description taken in connection with the accompanying drawing illustrating a preferred embodiment of the invention by way of example, and wherein:

Figure 1 shows a blank of one part of the frame ready to be bent;

Figure 2 is a fragmentary edge view of Figure 1 as indicated by arrow II;

Figure 3 is a section along line 3—3 of Figure 1;

Figure 4 is a face view of the U-shaped frame structure made by bending the blank of Figure 1;

Figure 5 is an end view of Figure 4 as indicated by arrow V;

Figure 6 shows a blank for closing the end of U-shaped frame of Figures 1—5;

Figure 7 is a top plan view of the frame structure made by bending the blank of Figure 6;

Figure 8 is a section taken on line VIII—VIII of Figure 7;

Figures 9 and 10 are fragmentary outer and inner face views showing the manner of assembling and securing the two frame parts; and

Figure 11 is a section taken along line XI—XI of Figure 10.

Referring to Figures 1 and 6 of the drawing, the filter frame is made of two separate sheet metal blanks or parts designated as A and B. Part A, shown in Figure 1, comprises a strip of dimensions suitable to make three walls of a filter frame such as the bottom wall 1 and the vertical side walls 2 and 3. On Figure 1, the transverse dot dash lines C between 1 and 2 and D between 1 and 3 indicate the places where the strip is to be bent to form the bottom corners while the longitudinal dot dash lines E on one side of 1, 2 and 3 and F on the other side thereof indicate where the strip is to be bent to form the front and rear face flanges 4, 4', 5, 5', 6 and 6'. When the strip is bent, it will form a C-shaped frame, as seen in Figure 4.

Centered on the corner bending lines C, D are 55 the dot and dash lines in Figure 4.

2

spear shape edge openings or slots 1, 1' and 8, 8', punched out to leave adjacent mitred edges 9 on wall 1 and 9' on walls 2 and 3 and transverse flange edges 11 on wall 1 and 11' on walls 2 and 3. The flange 5 has, adjacent slot 8 and along edge 11', a rectangular offset or embossed portion 12, having a length about equal to the width of flange 5 on wall 2. The depth to which 12 is offset or embossed is about equal to the thickness 10 of the sheet metal. The flange 5' of wall 2 and flanges 6, 6' of wall 3 are similarly embossed at 12.

When the strip is bent to form the flanged C-shaped frame shown in Figure 4, each embossed portion 12 will underlie the corresponding portions of wall 1 while edges 9, 9' will be in abutting relation. The frame is now spot welded at each embossed part 12.

The ends of side walls 2 and 3 have similar embossed pads 15, 15' on flanges 5 and 5' and 16, 16' 20 on flanges 6 and 6'.

Each of the side walls 2 and 3 is provided with a pair of parallel slits 17 near its outer or upper end. The metal between slits 17 is offset inwardly sufficiently to form an inner bridge band 18, which cooperates with the adjacent wall to form slot 19 as shown in Figure 3. Each bridge band 18 is formed with a hole 20. The bridge bands cooperate in securing the C-shaped frame and the top frame member as will be later described.

Part B, shown in Figure 6, comprises a strip dimensioned to provide the fourth or top wall 21 of the frame and to underlap the upper ends of the side walls thereof. On Figure 6, the transverse dot dash lines G and H indicate the places where 35 this strip is to be bent to form the top corners while the longitudinal dot dash lines J and K indicate the bending lines for the front and rear face flanges 22, 22'. When the bending operations are completed, the ends of the strip will be 40 downwardly turned to form flaps 25 having tongues 26. Tongue 26 has an H-shaped portion punched out to provide tabs 27 having cam edges 28. The H-shaped opening is slightly wider than opening 20.

In assembling the end wall 21, each tongue 26 is inserted in the adjacent bridge band slot 19 and its tabs 27 are bent or struck inwardly so that the cam edges 28 engage the upper edge of bridge band opening 20 with a camming action which 50 pulls these frame parts toward each other and locks them securely to each other. The embossed portions 15, 15' and 16 and 16' of side walls 2 and 3 receive the flanges 22, 22' in overlapping relation. The assembled relationship is shown by 55 the dot and dash lines in Figure 4.

In assembling the filter frame, the blank A is bent on the dot and dash lines C, D, E and F, into the form of a C-shaped channel member. Where the embossed portions 12 of walls 2 and 3 underlie the corresponding corner portions of flanges 4 and 4', the flanges are spot welded. This portion of the frame now can be painted or otherwise finished as required, and the filter element (not shown) then is inserted in the frame.

The part B is bent along the dot and dash lines G, H, J, and K, and then it is assembled onto part A by inserting tongues 26, into slots 19 with the corners of flanges 22, 22' overlying the embossed pads 15, 15' and 16 and 16'. By the use of a punch and hammer, the tabs 21 are peened or struck inward. In doing this, the cam edges 28 engaging the upper edges of holes 20 to cam the parts together and hold the part B in locked relationship on the rest of the frame. It will be understood that the overlapping corners of flanges 22, 22' and pads 15, 15' and 16, 16' may be spot welded together, if desired, and that the finishing operation on the frame may be carried out after the filter element is inserted. This structure provides an inexpensive frame which may be assembled quickly, with the parts fastened rigidly together.

I claim as my invention:

1. A filter frame comprising: a frame member extending circumferentially along a C-shaped path to form two sides and one end of a rectangular filter frame, the opposite end being open; an end member extending across and closing the open end of the filter frame, one end portion of

the end member being inturned to extend along the adjacent end portion of the adjacent side member; and means connecting the inturned end portion of the end member to the adjacent end portion of the adjacent side member, said means comprising a band struck out from one of said end portions to form a transverse bridge thereon and a slot between that bridge and that end portion, said bridge having an opening and a transverse edge along one side of that opening, the other adjacent end portion terminating in a tongue passing under the bridge and through the slot, the tongue having an opening under the bridge and transverse tabs secured to the tongue at the opposite ends of the tongue opening, said tabs being bent to extend into the bridge opening to interlock the parts together.

2. The frame of claim 1 wherein: each tongue tab has an edge extending at an angle to said transverse edge of the bridge opening and engaging that transverse edge to urge the end member toward the frame member by a cam action.
